US00D333144S

United States Patent [19]
Koizumi

[11] **Patent Number:** **Des. 333,144**
[45] **Date of Patent:** **** Feb. 9, 1993**

[54] **CHAMBER FOR SEMICONDUCTOR
FABRICATING MACHINE**

[75] **Inventor:** **Hiroyuki Koizumi, Tokyo, Japan**

[73] **Assignee:** **Canon Kabushiki Kaisha, Tokyo,
Japan**

[**] **Term:** **14 Years**

[21] **Appl. No.:** **676,068**

[22] **Filed:** **Mar. 27, 1991**

[30] **Foreign Application Priority Data**

Oct. 3, 1990 [JP] Japan 2-33476

[52] **U.S. Cl.** **D15/199**

[57] **CLAIM**

The ornamental design for a chamber for semiconductor fabricating machine, as shown and described.

DESCRIPTION

FIG. 1 is a front elevational view of a chamber for semiconductor fabricating machine showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a perspective view thereof.

*FIG. 1**FIG. 2**FIG. 3*

FIG. 4

FIG. 5

FIG. 6

FIG. 7
